UNITED STATES PATENT OFFICE.

CHARLES ERNEST DUUS, OF SOUTH BELGRAVIA, LONDON, ENGLAND.

FOLDING HOOD OR CANOPY.

1,165,233.

Specification of Letters Patent. Patented Dec. 21, 1915.

Application filed May 2, 1914. Serial No. 835,907.

To all whom it may concern:

Be it known that I, CHARLES ERNEST DUUS, a subject of the King of Great Britain, residing at 29^A Gillingham street, South Belgravia, in the county of London, England, have invented new and useful Improvements in or Connected with Folding Hoods or Canopies, of which the following is a specification.

10 This invention relates to hoods of that class which are provided with a forward extension adapted to cover the front part of the car. Hoods of this type are commonly known as "one man" hoods by reason of the facility with which they can be manipulated. In this class of hood in order to prevent the front or extension sagging it has hitherto been necessary to employ a knuckle or hinge butt joint in the horizontal 15 supporting arms to serve as a locking means. Joints of this character are expensive to produce and one of the objects of the present invention is to dispense with a joint of this type and to provide a more simple and 20 less expensive locking means and generally to simplify the construction of the device.

For convenience the invention will be described in connection with a motor carriage although it is equally applicable as a canopy 25 for seats.

In the accompanying drawings:—Figure 1 is a side elevation, partly in section, of a motor car fitted with a hood constructed according to the present invention. Fig. 2 is a similar view showing the principal parts of the framework of the hood separately. Fig. 3 is a plan thereof. Fig. 4 is a side elevation of part of a motor car showing the hood in its folded position. Fig. 5 is 30 a vertical transverse section taken on the line 1—1 of Fig. 2. Fig. 6 is a detail view of part of Fig. 4. Fig. 7 is a vertical transverse section taken on the line 2—2 of Fig. 6. Fig. 8 is a side elevation, partly in section, of a motor car fitted with a modified construction of hood. Fig. 9 is a similar view to Fig. 8 showing the principal parts of the framework of the hood separately. Fig. 10 is a side elevation of part of the car 35 showing the hood in its folded position, and Fig. 11 is a side elevation of part of a "two

seater" motor car having the present invention applied thereto in a slightly modified form.

In the several figures like parts are indicated by similar letters of reference and Figs. 2 to 4, 9, 10 and 11 are drawn to an increased scale, and Figs. 5 to 7 are drawn to a further increased scale with respect to the other figures of the drawings.

In carrying the invention into effect the following arrangement of parts is employed on each side of the vehicle as will be readily understood. Referring to Figs. 1 to 7 ⁵⁵ *a* represents the car body, *a'* represents the door for the entry of passengers, *a²* represents the door for the driver and *h* represents the cover of the hood. Pivotaly connected to the car body *a* at a point *b'* to the rear of the door *a'* is a back falling pillar *b* ⁶⁰ which with its fellow carries the main hoop stick *b²*. To the upper end of the back falling pillar *b* is pivotaly connected at *c'* one end of a long approximately horizontal arm *c* which is formed in two lengths or sections ⁶⁵ *c¹* and *c²* pivotaly connected together at *c²* and in the extended position of the hood this arm *c* has a slight sag at the joint *c²* as shown at Figs. 1 and 2. This horizontal arm *c* and the corresponding one on the other side ⁷⁰ of the car *a* carry the front hoop stick *c³*.

Pivotaly connected to the back falling pillar *b* at a point *d'* a short distance below the junction *c'* therewith of the long horizontal arm *c* is a stay *d* which has an upward inclination. This upwardly inclined stay *d* is pivotaly connected with the inner section of the horizontal arm *c* at a point *d²* about its mid-length and it is continued some distance beyond the point *d²* and at or near ⁷⁵ its extremity is pivotaly connected at *e'* to one end of a link *e* having a downward inclination and the other end of which link *e* is pivotaly connected at *e²* to the outer section of the horizontal arm *c* at about its mid-length. The second hoop stick *d³* is carried by the upwardly inclined stay *d* and its fellow on the other side of the car *a*.

That part of the upwardly inclined stay *d* between its point of connection *d²* with ⁸⁰ the horizontal arm *c* and the back falling pillar *b* is divided at the point *d⁴* and formed

with upwardly curved ends d^s , connected by a pivotal joint d^4 which in the extended position of the hood as shown at Figs. 1 to 3 abuts against the underside of the inner section of the horizontal arm c so as to form a lock and support the horizontal arm against sagging. This joint d^4 is also preferably provided with a pair of disks d^s , or it might be other like means, for embracing the horizontal arm c and preventing lateral movement of the device thereby stiffening the entire structure.

In the collapsed position of the hood as shown at Figs. 4 to 6 the curved parts d^s of the upwardly inclined stay d at the joint d^4 abut against the back falling pillar b and the horizontal arm c and prevents the other parts of the device and the hoop sticks from unduly creasing and chafing the cover of the hood and which is a common fault with car hoods.

The rear part of the hood beyond the back falling pillar b may be constructed in any usual way; in the present case a back stay f is at its lower end pivotally connected to the car body at b' and carries a hoop stick f' .

The hood may be easily collapsed by downwardly breaking the joint d^4 of the upwardly inclined stay d .

In the example given at Figs. 8 to 10 a slight modification is shown. In this case the lower end, beyond the point b' of the back falling pillar b is formed with a crank b^3 and the back stay f at its lower end is formed with a crank f^2 and is pivotally connected at f^3 with the crank b^3 of the back falling pillar b . By this construction in the collapsing of the hood the crank b^3 turns in a downward and forward direction carrying with it the back stay f and thus the hood is caused to fold in a more compact manner than by the arrangement described with respect to Figs. 1 to 7.

In the example given at Fig. 11 the back falling pillar b at its lower end is cranked at b^3 and pivotally connected to the lower end of the back stay f as hereinbefore described but in this case the back stay f is not cranked and a supplemental back stay g is employed which is pivotally connected at g' to the back stay f .

By the means hereinbefore described a hood of simple and effective form is obtained which is less costly to produce than existing devices of a similar type and which gives the maximum of rigidity to the structure.

What I claim is:—

1. In a carriage hood having a forward extension, a pair of back falling pillars hinged to the car body, a pair of long approximately horizontal arms pivotally connected to the back falling pillars and carrying a hoop stick, said arms being each formed in two lengths or sections jointed

together, upwardly-inclined stays pivotally connected with the back falling pillars at points below the junction therewith of the horizontal arms and also pivotally connected with the long horizontal arms at points to the rear of the joints of the latter, joints in said upwardly inclined stays to the rear of their pivotal connection with the long horizontal arms, said joints abutting against the long horizontal stays, and being provided with means for laterally embracing the same so as to laterally stiffen the structure, link connections between the long horizontal arms and the upwardly inclined stays near to the ends of the latter, said links having a rearward and upward inclination and a hoop stick carried by said upwardly inclined stays as set forth.

2. In a carriage hood having a forward extension, a pair of back falling pillars hinged to the car body, a pair of long approximately horizontal arms pivotally connected to the back falling pillars and carrying a hoop stick, said arms being each formed in two lengths or sections jointed together, upwardly inclined stays pivotally connected with the back falling pillars at points below the junctions therewith of the horizontal arms and also pivotally connected with the long horizontal arms at points to the rear of the joints of the latter, joints in said upwardly inclined stays to the rear of their pivotal connection with the long horizontal arms, said joints abutting against the long horizontal arms, disk like enlargements in each side of each of said joints adapted to embrace the long horizontal stays between them, link connections between the long horizontal arms and the upwardly inclined stays near to the ends of the latter, said links having a rearward and upward inclination and a hoop stick carried by said upwardly inclined stays as set forth.

3. In a carriage hood having a forward extension, a pair of back falling pillars hinged to the car body, a pair of long horizontal arms pivotally connected to the back falling pillars and carrying a hoop stick, said arms being each formed in two lengths or sections jointed together, upwardly inclined stays pivotally connected with the back falling pillars at points below the junction therewith of the long horizontal arms and also pivotally connected with the long horizontal stay at points to the rear of the joints of the latter, joints in the said upwardly inclined stays to the rear of their pivotal connection with the long horizontal arms, said joints abutting against the long horizontal stays, link connections between the long horizontal arms and the upwardly inclined stays near to the ends of the latter, said links having a rearward and upward inclination, a hoop stick carried by said up-

wardly inclined stays, rearwardly cranked extensions on the lower ends of the back falling pillars below their axes, a pair of back stays extending rearwardly and upwardly and at their lower ends downwardly and rearwardly cranked, pivotal connections between the extremities of said cranks and

the cranks of the back falling pillars and a hoop stick carried by said back stays as set forth.

CHARLES ERNEST DUUS.
